UNITED STATES PATENT OFFICE.

JAMES L. LEE, OF CHICAGO, ILLINOIS.

DESIGN FOR A PRINTER'S WRENCH.

SPECIFICATION forming part of Design No. 26,157, dated October 6, 1896.

Application filed June 27, 1896. Serial No. 597,260. Term of patent 7 years.

To all whom it may concern:

Be it known that I, JAMES L. LEE, a citizen of the United States, residing at Chicago, in the county of Cook and State of Illinois, have invented and produced a new, useful, and original Design or Shape for Printers' Wrenches, of which the following, in connection with the accompanying drawings, is a full, clear, and exact specification.

10 In the said drawings, Figure 1 is a side elevation of a printer's wrench embodying my design, and Fig. 2 is a plan view thereof.

The leading features of my design consist of a printer's wrench having the three projections A, B, and C each provided with an annular enlargement D.

15 The projection or portion A is in the form of a substantially cylindrical bar or rod, and the projections B and C are of substantially the same form and are constituted by a continuous rod or bar arranged at substantially right angles to the bar A, and with which the

bar A adjoins at an intermediate point between the annular enlargements D on the projections B and C. The outer end of the projection or portion A below the enlargement D is provided with longitudinal grooves a, which constitute four ribs, as indicated in dotted lines in Fig. 2.

20 The projection B from a point beyond the enlargement D is flattened, as shown at b, while the outer end of the projection C is slightly rounded, as shown at c.

Having thus described my invention, what I claim as new, and desire to secure by Letters Patent, is—

25 The new, useful and original design or shape for printers' wrenches, substantially as herein shown and described.

JAMES L. LEE.
